FORMING TOOL FOR REDUCING STOCK

Michael J. Kreutzer, Dayton, Ohio, assignor to
General Motors Corporation, Dayton, Ohio, a
corporation of Delaware

Application February 12, 1952, Serial No. 271,196

7 Claims. (Cl. 113—52)

1

This invention relates to refrigerating apparatus and more particularly to a method and a tool for spinning tubular stock for use in fabricating refrigerant filters and the like.

It is an object of this invention to provide a spinning device which is an improvement over spinning devices of the type shown in Hill Reissue Patent 22,465.

More particularly, it is an object of this invention to provide a spinning device and method which eliminates the need for the so-called "heat ring" of the Hill Reissue Patent No. 22,465 and which utilizes a spinning tool having a simple construction wherein the area of contact between the tool and the tubular stock constitutes considerably less than 50% of the circumference of the stock.

Another object of this invention is to provide a spinning device which requires so little pressure for its operation that it may be used in a conventional drill press.

Still another object of this invention is to provide a spinning device comprising a holder which removably supports a tube guide and a separate spinning insert.

A further object of this invention is to provide a simple and inexpensive spinning tool which is so constructed and arranged that successive portions of the stock to be spun are free to distort or deform during the spinning operation.

Still another object of this invention is to provide a spinning tool which not only serves to reduce the outer diameter of tubular stock but also serves to form an internal shoulder on the tubular stock.

Further objects and advantages of the present invention will be apparent from the following description, reference being had to the accompanying drawings wherein a preferred form of the invention is clearly shown.

In the drawings:

Figure 1 is a vertical sectional view showing a preferred embodiment of the invention.

Figure 2 is an end elevational view showing the shape of the spinning insert.

Figure 3 is a sectional view with parts broken away and taken substantially on line 3—3 of Figure 1.

Figure 4 is a fragmentary elevational view with parts broken away showing a section of tubing which has had its one end reduced by means of the device shown in Figures 1 through 3 and showing the internal shoulder arrangement for positioning a strainer element within the tubing.

In manufacturing various types of small tubu-

2

lar housings, it is standard practice to place a length of tubular stock in a holder and to exert a reducing pressure on the stock by means of a spinning tool as the tubular stock and the tool are relatively rotated and moved toward each other. The spinning tools used in the process are usually provided with an annular portion which gradually decreases in cross-section and thereby exerts a reducing pressure continuously around the entire circumference of the stock to progressively heat the latter to an easily workable condition. Prior to this invention it was considered necessary to have the spinning device exert a very high pressure on the surface being shaped and to engage the stock throughout a major portion of the circumference whereas it has been discovered that a spinning tool having a plurality of properly designed relatively narrow axially extending rib portions for engaging the stock can be used very effectively to reduce the diameter of tubular stock. As will be explained more fully hereinafter, the stock engaging ribs are relatively straight-sided so as to engage the stock along a straight line.

Referring now to the drawing wherein there is shown a preferred embodiment of the invention, reference numeral 10 generally designates a holding fixture which is provided with a spindle 12 for use in mounting the holding fixture or adapter in a conventional drill press. The adapter 10 serves to support a spinning insert 14 and a pilot element 16 as best shown in Figure 1. The spinning insert 14 is provided with a central bore for receiving the stock to be spun. The reduced end of the tubing moves into the space between the spinning insert and the pilot element 16. The central bore consists of a first portion 18 of substantially uniform diameter and a second tapered portion 20 which is somewhat oval in cross-section as best shown in Figure 2 of the drawing.

By virtue of the oval shape of the spinning insert, it is obvious that it will engage the tubing only adjacent the side portions 22 which project slightly as shown and which constitute rib-like formations for engaging the tubing. As best illustrated in Figure 2 of the drawing, the rib portions 22 are diametrically opposite one another so as to engage the opposite sides of the tubing along a narrow region extending substantially axially. The tubular stock is free to expand as it moves past each rib portion 22 due to the oval shape of the tapered bore 20. The repeated expansion and recompression of the tubular stock

generates heat which facilitates working the stock.

A guide ring 30 has been provided as shown and serves to guide the stock as it is fed into the spinning insert. This ring does not contact the stock throughout its entire circumference but can only contact the stock along three spaced points as best illustrated in Figure 3 of the drawing as approximately two-thirds of the inner surface of the guide ring has been cut away as indicated at 32. The minimum internal diameter of the guide ring is preferably slightly greater than the outer diameter of the tubular stock so as to prevent binding. The guide ring is made separate from the spinning insert 14 with the result that it is not necessary to replace the guide ring when replacing the spinning insert and vice versa. Furthermore, by making the guide ring as a separate element it simplifies the manufacture of the spinning insert. The adapter 10 is provided with lugs 35 which engage within slots 37 formed in the outer periphery of the guide ring 30 as shown in Figure 3. A retaining cap or ferrule 39 is provided as shown for removably holding the guide ring 30, the spinning insert 14 and the pilot 16 in place in the fixture 10.

Figure 4 shows a section of tubing 40 which has had its one end 42 reduced in diameter by means of the device shown in Figures 1 through 3. Spinning devices of the type shown herein may be used to reduce the diameter of tubing for many different uses, but for purposes of illustrating the invention Figure 4 shows a portion of a filter for use in a refrigerating system.

The pilot element 16 serves to engage the inner circumference of the tubing after it has had its diameter reduced by the spinning insert 14. It will be noted that the leading end of the pilot element is of a reduced diameter whereby a shoulder 34 is formed on the pilot which in turn serves to form a shoulder 36 (see Figure 4) internally of the tube. This shoulder 36 then serves as a stop or positioning means for use in positioning the strainer element 38 within the reduced portion 12 of the tubing.

The pilot element 16 is provided with hardened inserts 44 which resist wear better than the rest of the main body of the pilot. These inserts are preferably made of tungsten carbide. The opposite sides the pilot have been flattened as shown so as to reduce the possibility of binding between the tubing and the pilot. The flattened sides may also be used as passages for a cooling fluid in those installations in which a cooling fluid is circulated through the tubular stock during the spinning operation.

While the form of embodiment of the invention as herein disclosed constitutes a preferred form, it is to be understood that other forms might be adopted as may come within the scope of the claims which follow.

What is claimed is as follows:

1. In a forming tool for reducing the diameter of tubular stock, a spinning element having an axially extending cavity at least a portion of which is of progressively diminishing cross-section longitudinally of the element, the wall of said cavity being adapted to engage and reduce the stock upon relative rotation and axial movement toward one another of the stock and tool, said wall being provided with relief recess means extending longitudinally substantially throughout the length of said cavity, the area of the stock engaging wall of the cavity being substantially

tially less than the area of said relief recess whereby only a minor portion of the circumference of the stock is engaged by the element during the reducing operation leaving the remaining portion free to deform into said relief recess in response to the reducing operation, and a pilot element projecting into said cavity for limiting the internal diameter of the deformed stock, said pilot element having a shoulder formed thereon so as to form a shoulder on the internal surface of said stock.

2. In a forming tool for reducing the diameter of tubular stock, a spinning element having an axially extending cavity at least a portion of which is of progressively diminishing cross-section longitudinally of the element, the wall of said cavity being adapted to engage and reduce the stock upon relative rotation and axial movement toward one another of the stock and tool, said wall being provided with relief recess means extending longitudinally substantially throughout the length of said cavity, the area of the stock engaging wall of the cavity being substantially less than the area of said relief recess whereby only a minor portion of the circumference of the stock is engaged by the element during the reducing operation leaving the remaining portion free to deform into said relief recess in response to the reducing operation, a pilot element projecting into said cavity for limiting the internal diameter of the deformed stock, said pilot element having a shoulder formed thereon so as to form a shoulder on the internal surface of said stock, and an insert of relatively wear-resistant material in the face of said pilot at the place where the pilot first engages the interior of the oncoming stock.

3. In combination, a forming tool for reducing stock having an axially extending cavity at least a portion of which is of progressively diminishing cross-section longitudinally of the tool, the wall of said cavity being adapted to engage and reduce the stock upon relative rotation and axial movement toward one another of the stock and the tool, said wall being provided with a plurality of relief recesses separated by substantially straight sided ribs extending longitudinally substantially throughout the length of said portion of progressively diminishing cross-section, said relief recesses comprising a major portion of the inner circumference thereof, a holder for removably supporting said forming tool, and guide means for said stock removably carried by said holder, said guide means comprising a ring having a plurality of inwardly extending projections for engaging the stock at spaced points about its periphery.

4. In combination, a forming tool for reducing stock having an axially extending cavity at least a portion of which is of progressively diminishing cross-section longitudinally of the tool, the wall of said cavity being adapted to engage and reduce the stock upon relative rotation and axial movement toward one another of the stock and the tool, said wall being provided with a plurality of relief recesses separated by substantially straight sided ribs extending longitudinally substantially throughout the length of said portion of progressively diminishing cross-section, said relief recesses comprising a major portion of the inner circumference thereof, a holder for removably supporting said forming tool, guide means for said stock removably carried by said holder, said guide means comprising a ring having a plurality of inwardly extending projections for en-

gaging the stock at spaced points about its periphery, and a pilot element removably carried by said holder for engaging the inner periphery of said stock.

5. In combination, a forming tool for reducing stock having an axially extending cavity at least a portion of which is of progressively diminishing cross-section longitudinally of the tool, the wall of said cavity being adapted to engage and reduce the stock upon relative rotation and axial movement toward one another of the stock and the tool, said wall being provided with a plurality of relief recesses separated by substantially straight sided ribs extending longitudinally substantially throughout the length of said portion of progressively diminishing cross-section, said relief recesses comprising a major portion of the inner circumference thereof, a holder for removably supporting said forming tool, guide means for said stock removably carried by said holder, said guide means comprising a ring having a plurality of inwardly extending projections for engaging the stock at spaced points about its periphery, and a pilot element removably carried by said holder for engaging the inner periphery of said stock, said pilot element having portions of its periphery spaced from the inner wall of the stock so as to prevent seizure between the pilot and the stock.

6. In combination, a forming tool for reducing stock having an axially extending cavity at least a portion of which is of progressively diminishing cross-section longitudinally of the tool, the wall of said cavity being adapted to engage and reduce the stock upon relative rotation and axial movement toward one another of the stock and the tool, said wall being provided with a plurality of relief recesses separated by substantially

straight sided ribs extending longitudinally substantially throughout the length of said portion of progressively diminishing cross-section, said relief recesses comprising a major portion of the inner circumference thereof, a holder for removably supporting said forming tool, guide means for said stock removably carried by said holder, said guide means comprising a ring having a plurality of inwardly extending projections for engaging

10 the stock at spaced points about its periphery, and a pilot element removably carried by said holder for engaging the inner periphery of said stock, said guide means having a portion in engagement with a portion of said pilot so as to hold said pilot in position within said holder.

15 7. In combination, a forming tool having a cavity for receiving and reducing the diameter of tubular stock, guide means separate from said forming tool for directing the incoming stock into said cavity, and a holder having a socket for receiving said forming tool and said guide means, said holder including a removable clamping means for removably clamping said guide means and said forming tool in place within said holder, said guide means comprising a ring having means for engaging said tubular stock throughout less than 360° of its circumference.
